PLOWLIKE SCRAPER FOR CLEANING INTERIOR SURFACES OF WATER MAINS AND OTHER PIPES

Lawrence R. Robinson, Mount Lebanon, Kyle I. Robinson, Glenshaw, Earl O. Berger, Bellevue, and Walter S. Lang, Pittsburgh, Pa., assignors to Pittsburgh Pipe Cleaner Company, Pittsburgh, Pa., a corporation of Pennsylvania

Application December 20, 1946, Serial No. 717,544

13 Claims. (Cl. 15—104.16)

1

This invention relates to pipe cleaning tools or plow-like scrapers for cleaning the inner surfaces of water mains and other pipes, more particularly those with uneven inner surfaces.

The practice of cleaning hard deposits from the inner surfaces of pipe conduits by moving scrapers through the pipes is well known. A common form of cleaning apparatus is described in Haydock Patents 1,531,439 and 1,593,072. Such apparatus includes a flexible hollow stem or spring steel coil about the circumference of which are mounted a number of rearwardly diverging leaf springs carrying plow-like scrapers on their outer ends. Mounted on the hollow stem behind the plows are one or more cup-like pistons of flexible material. Water pressure behind the pistons forces them and the scraper plows through the pipe. The plows will cut through the deposits in the pipe and scrape it quite clean, unless there are pits or other depressions in the pipe surface which the plows can not enter. If rivet heads are inside the pipe the plows may slide over some of them without cleaning between them. When a pipe is being cleaned preparatory to being coated inside with a protective coating, it is quite important that all surfaces and depressions be scraped clean if possible. Some cleaning tools are provided with separate spring fingers to aid the plows, but such fingers are rather stiff and increase the length of the tools or form separate tools which must follow the plows. It also has been found that the spring fingers often are bent back so far by the projections in the pipe that the fingers break. Further, the fingers which ride along and scrape the bottom of the pipe and those which contact the outside bend of the pipe as the cleaner is moved around such a bend are subjected to a great deal of pressure which flattens the fingers and causes breakage.

It is an object of this invention to provide a pipe cleaning tool on which are mounted resilient scraping members adapted to clean in and around irregularities of the pipe's inner surface. Another object is to provide such a tool in which the resilient scraping members are protected from breakage.

According to the invention, the plow has a base from which project a pair of forwardly converging side walls whose outer edges are adapted to cut through the layer of foreign matter inside the pipe as the plow is moved through the pipe. A plurality of spring fingers are carried by the plow between its side walls. When unrestrained, these fingers will project outwardly beyond the

2

side wall cutting edges, and therefore they will spring into any pipe depressions that the cutting edges of the plow can not enter. On the other hand, the plow's side walls limit the amount that projections in the pipe can bend the fingers, whereby breakage of the fingers is substantially avoided.

The invention is illustrated in the accompanying drawings, of which Fig. 1 is a fragmentary 10 longitudinal section through a pipe showing two scraper plows engaging its inner surfaces; Figs. 2 and 3 are side and plan views, respectively, of one embodiment of the invention; Figs. 4 and 5 are plan and side views, respectively, of another 15 embodiment; Figs. 6 and 7 are plan and end views, respectively, of a further modification of the invention; and Fig. 8 is a side view of the third embodiment with the rear portions of the plow's side wall cut away.

20 Referring to Figs. 1, 2 and 3 of the drawings, the plow has a triangular base 1 with side walls 2 substantially perpendicular to the base and converging toward its apex. The outer edges of the side walls preferably are serrated or provided with saw teeth 3 for cutting through and 25 loosening deposits on the inner surface of a pipe. However, for the purposes of this invention, such edges can be smooth in which case they will cut more as a knife than as a saw. Attached 30 to the apex or front end of the plow by means of a metal plate 4 is an inclined metal loop 5. When plows like this are used in cleaning apparatus, such as the Haydock tool referred to above, leaf springs 6 (Fig. 1) diverging rearwardly from the central supporting hollow stem 35 (not shown) extend through the loops 5 and have their outer ends secured to the plow bases. While the tool is being moved through a pipe to clean it, springs 6 are bowed backwardly by the 40 plows which the pipe wall holds substantially parallel to the pipe axis. Thus, the leaf springs press the plows outwardly with considerable force.

45 It is a feature of this invention that this plow will clean out depressions in the pipe wall not reached by teeth 3. For this purpose a plurality of spring fingers 8 are mounted on base 1 between side walls 2, and these fingers will project beyond the teeth if not restrained. The 50 front ends of the fingers are secured by rivets 9 or other suitable means to the plow base from which they curve rearwardly and outwardly so as normally to extend beyond teeth 3 in a direction substantially perpendicular to the base, as shown in Fig. 2. Preferably, as shown in Fig.

3, the fingers are arranged in rows extending across the base with the fingers in each row staggered relative to those in the adjacent rows.

The operation of the spring fingers is illustrated in Fig. 11 where two plows are shown in tandem, although usually the second plow will follow between two plows ahead of it. The plows cut through the deposit (not shown for the sake of clearness) to the inner surface of the pipe along which the teeth scrape. The outer ends of the spring fingers likewise scrape along the pipe surface by which they are pressed inwardly between the side walls of the plow. When the plow reaches a depression, such as a pit 10, its teeth will pass over the pit without cleaning it. However, one or more of the spring fingers, being urged outwardly by their own resiliency will spring into the pit and scrape foreign matter from it. Similarly, as a plow passes over a projection, such as a rivet 11, the plow will be tilted or pushed away from the pipe wall momentarily by the rivet, with the result that certain areas of the pipe may not be scraped by the plow teeth. The spring fingers, however, will reach those areas and clean around the rivet.

An advantage of mounting the spring fingers in the plow is that the distance they can be bent back toward the plow base, that is, the amount they can be straightened is limited by the plow's side walls which space its base from the pipe wall. This precludes breakage of the fingers which has been a problem where the fingers were independently mounted and could be overstressed in passing over projections. Even in cases where it may not be necessary to protect the spring fingers from breakage, there are advantages in mounting a relatively large number of fingers close together in a small space on a supporting base or plate attached to the outer end of a leaf spring. It permits the use of fingers that are more flexible than larger ones and which will accommodate themselves to the pipe and scrape it clean.

In the modification shown in Figs. 4 and 5 the plow has a forwardly tapered base 15 and converging side walls 16 with serrated cutting edges 17, like the plow described above. The spring fingers 18, however, instead of being separate curved springs attached directly to the plow base, are integral with the rear end of a separate triangular plate 19 bolted or riveted to the base between its side walls. The fingers are formed by longitudinally slitting the back portion into parallel strips which then are twisted 90° and bent upwardly so that they will extend outwardly beyond the side wall cutting edges. In operation, the spring fingers normally are pressed by the pipe wall inwardly between the side walls of the plow. On encountering depressions in or projections on the pipe surface the spring fingers move outwardly or inwardly to clean those areas in the manner previously described. Over-bending of these fingers is avoided by the side walls and base of the plow. Spring cutters of this type are advantageously used when cleaning particularly hard layers of foreign substance from a pipe. Also, they are useful for small pipe when the plows are too small to accommodate several rows of spring fingers.

The third embodiment of the invention, illustrated in Figs. 6 to 8, is particularly useful when large conduits are to be cleaned. The tapered base 21 of the plow shown there supports a forwardly tapering plate 22 bolted thereto. Welded to the marginal areas of the plate are pairs of lugs 23 provided with openings through which

headed retaining members or pins 24 extend. The pins are parallel and are maintained in position by cotter pins 26 or the like. Each pin supports a series of spring fingers 27 formed from lengths of spring wires or rods, the inner ends of which are mounted in holes in the plate directly behind the pin. The fingers extend straight away from the plate and then are curved forwardly across the pin and back between the plate and pin from which they then curve outwardly and forwardly. After making such a loop or coil about the pins, the free ends of the fingers extend outwardly beyond the outer edge of the plow's side walls a sufficient distance to function in the same manner as the spring fingers of the embodiments previously described. An advantage of looping the fingers about the pins in the direction shown is that when their outer ends are pressed rearwardly and inwardly, the coils about the pins are enlarged or loosened instead of being tightened which might break the fingers at the coils. The side walls 28 of the plow prevent fingers 27 from being bent too far and possibly being broken.

According to the provisions of the patent statutes, we have explained the principle, construction and mode of operation of the invention and have illustrated and described what we consider its preferred embodiments. However, it is to be understood that, within the scope of the appended claims, the invention may be practiced by other forms than those specifically illustrated and described.

We claim:

1. A plow adapted to be moved through a pipe having an uneven inner surface to scrape foreign matter from that surface, said plow comprising a base, a pair of forwardly converging side walls substantially perpendicular to said base and having outer edges adapted to cut through said foreign matter, and a plurality of spring fingers mounted between said side walls and urged outwardly beyond said cutting edges to clean foreign matter from pipe depressions not reached by said edges, said side walls limiting the distance said fingers can be bent toward the base, whereby breakage of the fingers is avoided.

2. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, and a plurality of curved spring fingers mounted between said side walls with their outer ends urged outwardly beyond said cutting edges to clean foreign matter from pipe depressions not reached by said edges, said fingers being disposed in staggered relation, and said side walls limiting the distance said fingers can be bent toward the base, whereby breakage of the fingers is avoided.

3. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, and a plurality of spring fingers mounted between said side walls and curved rearwardly and outwardly with their outer ends urged outwardly beyond said cutting edges to clean foreign matter from pipe depressions not reached by said edges, said side walls limiting the distance said fingers can be bent

toward the base, whereby breakage of the fingers is avoided.

4. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, a plate attached to said base between said side walls, and spring fingers integral with said plate and having cutting ends urged outwardly beyond said cutting edges to clean foreign matter from pipe depressions not reached by said edges, said side walls limiting the distance said fingers can be bent toward the plate by pipe projections encountered by the fingers, whereby breakage of the fingers is avoided.

5. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, and a metal plate attached to said base between said side walls, the rear end portion of the plate being divided lengthwise into a plurality of spring fingers that are bent outwardly to provide cutting ends urged outwardly beyond said cutting edges for cleaning foreign matter from pipe depressions not reached by said edges, said side walls limiting the distance said fingers can be bent toward the plate by pipe projections encountered by the fingers, whereby breakage of the fingers is avoided.

6. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, and a metal plate attached to said base between said side walls, the rear end portion of the plate being divided lengthwise into a plurality of strips that are twisted and bent outwardly to provide cutting ends urged outwardly beyond said cutting edges to clean foreign matter from pipe depressions not reached by said edges, said side walls limiting the distance said cutting ends can be forced toward the plate by pipe projections encountered by said ends, whereby breakage of the strips is avoided.

7. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, spaced retaining members extending across said base between said side walls, and a plurality of spring fingers wound about each of said retaining members with the outer ends of the fingers urged outwardly beyond said cutting edges to clean foreign matter from pipe depressions not reached by said edges, said side walls limiting the distance the outer ends of said fingers can be bent toward the base by pipe projections encountered by the fingers, whereby breakage of the fingers is avoided.

8. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut

through said foreign matter, a plate secured to said base between said side walls, spaced retaining members extending across said plate, means connecting said members to the plate in spaced relation thereto, and a plurality of spring rods coiled around each retaining member, the inner ends of the rods being connected to said plate, and the outer ends of the rods being urged outwardly beyond said cutting edges to clean foreign matter from pipe depressions not reached by said edges, said side walls limiting the distance said outer ends of the rods can be pressed toward the plate by pipe projections encountered by the rods, whereby breakage of the rods is avoided.

15 9. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, a plate secured to said base between said side walls, spaced retaining members extending across said plate, means connecting said members to the plate in spaced relation thereto, said plate being provided with a plurality of holes adjacent said members, and a plurality of spring rods having their inner ends mounted in said holes, said rods being coiled around said retaining members with the outer ends of the rods urged outwardly beyond said cutting edges to clean foreign matter from pipe depressions not reached by said edges, said side walls limiting the distance said outer ends of the rods can be bent toward the plate by pipe projections encountered by the rods, whereby breakage of the rods is avoided.

20 10. In a pipe cleaning tool adapted to be moved through a pipe to scrape foreign matter from the inner surface thereof and having a plurality of rearwardly diverging leaf springs, a base member supported by the outer end of each of said leaf springs, a pair of forwardly converging side walls substantially perpendicular to said base and having outer edges adapted to cut through said foreign matter, and a plurality of spring teeth mounted on each of said base members and curved rearwardly and outwardly with their outer ends urged outwardly beyond said cutting edges to scrape foreign matter from the pipe, said side walls limiting the distance said fingers can be bent toward the base.

25 11. In a pipe cleaning tool adapted to be moved through a pipe to scrape foreign matter from the inner surface thereof and having a plurality of rearwardly diverging leaf springs, a base member supported by the outer end of each of said leaf springs, a pair of forwardly converging side walls substantially perpendicular to said base and having outer edges adapted to cut through said foreign matter and a plurality of spring teeth mounted on each of said base members and curved rearwardly and outwardly with their outer ends urged outwardly beyond said cutting edges to scrap foreign matter from the pipe, said fingers being disposed in staggered relation, and said side walls limiting the distance said fingers can be bent toward the base.

30 12. In a pipe cleaning tool adapted to be moved through a pipe to scrape foreign matter from the inner surface thereof and having a plurality of rearwardly diverging leaf springs, a forwardly tapered base member supported by the outer end of each of said leaf springs, a pair of forwardly converging side walls substantially perpendicular to each of said base members, said

side walls having outer edges adapted to cut through said foreign matter, spaced retaining members extending across each of said base members, means connecting said retaining members to the base member in spaced relation thereto, and a plurality of spring rods having their inner ends connected to said base member directly behind each of said retaining members, said rods extending away from the base member and forwardly across said retaining members and then rearwardly between said base and retaining members and then curving outwardly and forwardly with their outer ends adapted to scrape foreign matter from the pipe, said side walls limiting the distance said outer ends of the rods can be forced toward the plates by projections encountered by the rods, whereby breakage of the rods is avoided.

13. A plow adapted to be moved through a pipe having an uneven inner surface to scrape foreign matter from that surface, said plow comprising a forwardly tapered base, a pair of forwardly converging side walls substantially perpendicular to said base and having outer edges adapted to cut through said foreign matter, and a plurality of spring fingers arranged in laterally extending rows and secured to said base, said fingers being staggered with respect to each other and being curved from the base rearwardly and outwardly, the outer ends of the fingers be-

ing urged outwardly beyond said cutting edges of the side walls to clean foreign matter from pipe depressions not reached by said edges, said side walls limiting the distance the fingers can be bent, whereby breakage of the fingers is avoided.
